[57] CLAIM

The ornamental design for a rotatable tray, as shown and described.

DESCRIPTION

FIG. 1 is a top perspective view of the rotatable tray showing my new design;

FIG. 2 is a top plan view thereof;

FIG. 3 is a bottom plan view thereof;

FIG. 4 is a side elevational view, the other sides being identical thereto; and,

FIG. 5 is a cross-sectional view taken along line 5—5 of FIG. 2.

FIG. 1

FIG. 2

FIG. 3

FIG. 4

FIG. 5
